UNITED STATES PATENT OFFICE.

MARTIN ANDREW JOHNSON, OF WATERFORD, CALIFORNIA.

WIRE-STRETCHER.

No. 882,149.

Specification of Letters Patent.

Patented March 17, 1908.

Application filed May 6, 1907. Serial No. 372,166.

To all whom it may concern:

Be it known that I, MARTIN ANDREW JOHNSON, a citizen of the United States, residing at Waterford, in the county of Stanislaus and State of California, have invented a new and useful Wire-Stretcher, of which the following is a specification.

The present invention relates to improvements in devices for tensioning or stretching wires and similar purposes, and is especially adapted for use in tensioning or tightening the strand wires of fencing, and it has for its object to provide an improved device of this character that is capable of firmly engaging the wire without liability of unduly cutting or breaking it, and when the draft is applied will cause the wire to be drawn in a straight line so as to prevent kinking and twisting of the wire, the device being composed of a few simple parts so constructed and arranged that they cannot get out of order.

To these and other ends, the invention comprises the various novel features of construction and combination and arrangement of parts, which will be hereinafter more fully described and pointed out particularly in the claims appended hereto.

In the accompanying drawings:—Figure 1 is a side elevation of a wire stretcher constructed in accordance with my present invention, the dotted lines indicating the relative position of the wire. Fig. 2 is a bottom plan view of the device shown in Fig. 1. Fig. 3 is a section on the line 3—3 of Fig. 1 looking in the direction of the arrows.

Corresponding parts in the several figures are indicated throughout by similar characters of reference.

The device shown in the present embodiment of the invention is especially adapted for use in stretching the strand wires of wire fencing by the aid of a block and tackle or a horse, and it comprises, in the present instance, a yoke 1 of approximately semi-circular form and having a substantially flat portion, the greater dimension extending in a direction parallel to the plane of curvature, the width of the yoke iron decreasing to form a taper at one end of the yoke where an eye 2 is formed to slidably receive a draw rod 3, the opposite end of the yoke being relatively heavy and provided with an out-turned extension or enlargement 4. The axis of the eye 2 extends at a slight or very acute angle to the plane of the yoke and arranged upon the front surface 5 of the yoke

and adjacent enlargement 4 is a lateral projection 6 forming a relatively fixed jaw, the outer edge of which is in a plane parallel to the axis of the eye 2 and to the bar 3. This 60 enlargement or jaw has a substantially smooth operating face 7 adapted to receive the wire x.

Mounted in coöperative relation with the relatively fixed jaw is a movable jaw 8, a pivot pin 9 passing through the yoke and a reinforcing bracket 10 thereon and serving as a pivotal mounting for the movable jaw. The operating face 11 of the relatively movable jaw is formed eccentrically of its pivot, 70 that is to say, its axis of movement, and it is also preferably roughened or serrated in order that it may obtain a firm hold on the wire that is clamped between it and the relatively fixed jaw. The upper end of the 75 movable jaw is provided with an operating extension 12 which is operatively connected to the bifurcated end 13 of the draw-rod by means of a pivot 14, reciprocation of the latter through the eye of the yoke serving to 80 turn or operate the movable jaw about its axis, the eccentrically formed operating face of the movable jaw serving to grip and release the wire that is interposed between it and the relatively fixed jaw. The draw-rod 85 is so connected to the relatively movable jaw that it cannot rotate on its longitudinal axis, and in order to facilitate the attachment of a suitable tackle thereto, it is provided on its outer end with an eye 15 in which is fitted an 90 attaching ring 16.

In using a wire attaching device constructed in accordance with the invention, for tensioning the strand wires of fences, the draw rod is pushed inwardly relatively to the 95 yoke in order to turn the movable jaw to open position, and after the wire has been inserted between the movable jaw and the stationary jaw, the tackle is attached to the ring on the draw rod, and as the draft is applied, the tension of the draw rod will operate to draw the upper end of the movable jaw forwardly, the operating face of the movable jaw being moved in a direction that will cause it to firmly grip the wire, the tension or 105 draft applied to the device serving not only to retain the jaws in coöperative relation with the wire, but also to effect the tensioning thereof. After the proper tension has been obtained and the wires have been suitably fastened, the draw rod is pushed inwardly, causing a separating movement be- 110

tween the roughened surface or operating face of the movable jaw and the wire that will serve to disengage them. As the relative arrangement of the jaws permits the wire to be clamped between them while extending in a direction parallel to the axis of the draw rod, kinking or bending of the wire is prevented, and as the attaching ring cannot rotate about the draw rod as an axis, twisting of the wire is prevented.

Importance is attached to the provision of a yoke constituting the body of the device because the wire to be stretched is thus extended across the space within the yoke and should the wire contain a large twist or knot it would not tend to prevent the wire from being properly seated on the extension or jaw 6 but would instead rest within the space in the yoke.

20 What is claimed is:—

A wire stretcher comprising a yoke having an enlargement at one end and an eye at the other end, a draw bar slidably mounted with-

in the eye, the axis of the eye being disposed at an acute angle to the plane of the yoke, a 25 projection upon one face of the yoke and adjacent the enlargement, said projection being disposed in a plane parallel to the axis of the eye and to the bar, a reinforcing bracket secured upon one side of the yoke and adjacent 30 the enlargement, a coöperating jaw pivoted within the bracket and having an operating face disposed to clamp a wire upon the projection, and an arm extending from the pivoted jaw and pivotally connected to the draw 35 bar, the operating face of the projection being disposed on a straight line extending across the space within the yoke.

In testimony that I claim the foregoing as my own, I have hereto affixed my signature 40 in the presence of two witnesses.

MARTIN ANDREW JOHNSON.
